Filed June 10, 1965, Ser. No. 462,812
4 Claims. (Cl. 169—17)

ABSTRACT OF THE DISCLOSURE

Condensate collector for a dry pipe sprinkler system having draining means and venting means and a funnel filling means for adding antifreeze liquid for cold weather fire protection.

This invention relates to apparatus for the introduction, control, removal and replacement of antifreeze in dry pipe sprinkler systems to prevent condensate from freezing and destroying the fluid tight integrity of the system.

A dry pipe sprinkler system is used for fire prevention in such buildings as boat houses, yacht clubs, and the like. In such systems, the pipes are charged with compressed air and fusible plugs in the system, when melted by heat from a fire, for example, allow the gas pressure to drop and thereby enable the opening of a water valve which in turn delivers water to the system for fire control.

To compensate for loss of air pressure through inevitable small leaks, an air compressor or similar charging system is used. Small amounts of moisture are thereby introduced into the system, which upon condensation collect in the low points of the system.

In the past, the means for collecting the water at the low points and maintaining the collected water at above-freezing temperatures was cumbersome, expensive and fraught with regulatory approval and maintenance problems. My invention provides for collecting the condensate and treating it with antifreeze, obviating the need for heat and minimizing the other problems.

The main objects of the present invention are to provide means for introducing antifreeze into the low point of dry pipe sprinkler systems, to provide a collector in which condensate arriving at the low point can mix readily with the antifreeze, and to provide means for efficiently removing the diluted antifreeze and replacing it.

Further objects of this invention are to provide means for testing the degree of dilution of the antifreeze-condensate mixture before draining it from the system, to avoid discarding it prematurely, and, in recharging the system with antifreeze, to provide means for indicating that the system has received its proper volume of antifreeze.

It is the ultimate intent of this invention to satisfy the aforementioned objects by means of one single simple piece of apparatus and not a complicated system of disconnected valves and piping.

Governing bodies can inspect and test the apparatus and, when it meets their requirements, can mark it approved with the knowledge that, all parts being united in the one piece of apparatus, no essential disconnected pipe or valve can be omitted.

Once the apparatus has received the mark of approval of the governing bodies, installing contractors are assured, and can assure their clients, that the applicable sprinkler system with the approved apparatus properly installed will be approved in this respect as a system, whereas such approval could not be given for a system of disconnected piping and valves which might be devised to serve the same purpose, without special inspection.

The owner of a building in which such sprinkler system is installed readily recognizes the value of an

2

approved piece of equipment with its simplified operating instructions.

It is a further object of this invention to provide a condensate collector for a pressurized pipe system comprising a hollow drum having a top portion, a bottom portion and sidewalls, the drum being in communication with the pipe system through an opening in the top portion thereof, and through a suitable valve. The drum has a drain valve in the bottom portion and a vent valve in the top portion thereof. Suitable filler means comprising a valve and a funnel having indicia means thereon are located in the sidewall of said body.

The present invention, both as to its organization and manner of operation together with further objects and advantages thereof, may best be understood by reference to the following description taken in connection with the accompanying drawing which is a cross-sectional view in elevation of the condensate collector partially filled with antifreeze.

20 The condensate collector as shown in the drawing comprises a hollow drum generally indicated by the numeral 10, having a top portion 11, a bottom portion 12, and a sidewall 13. The drum 10, as shown, is in fluid communication with a dry pipe sprinkler system schematically indicated by numeral 32, through the opening 15 and shut-off valve 14 in the top portion 11 which connects with conduit 16.

A vent valve 17 is provided in the top portion of the drum 10. The vent valve 17 comprises a handwheel 18 and stem 19 threaded into the valve housing 20 and seating at 21. When the valve stem 19 is unseated, a passage-way is opened from the inside of drum 10 through opening 22 in the side of the valve stem 19 and through the longitudinal passage 23 in valve stem 19 and into the atmosphere.

30 Drain valve 24 is located at the lowermost part of the bottom portion 12 of the drum 10 and is substantially identical to the valve 17. It is to be understood that any suitable valve may be used in place of the ones disclosed herein.

40 Filling means is provided in the sidewall of the drum 10. The filling means comprises an upstanding funnel 26 and a valve 25 which is similar to above-described valves 17 and 24. The funnel 26 communicates with the inside of drum 10 when the solid stem 27 is unseated from valve seat 21. The communication is set up through the opening 28 in the sidewall 13 defined by the valve seat 21. The funnel 26 may be provided with a cap 29 to keep out any foreign matter. Fluid level indicia means 30 is embossed on the inside surface of the funnel 26 for the purposes that will become obvious in the description of the operation of the device.

45 In use, condensate from the sprinkler system 32 enters drum 10 through normally open valve 14 and opening 15. To prevent the condensate from freezing, the drum 10 is partially filled with an antifreeze solution 31. The filling is accomplished by first closing shut-off valve 14 to prevent bleeding of the compressed air in the system 32. Vent valve 17 and fill valve 25 are then opened. The drum 60 is drained by opening valve 24; after draining, valve 24 is closed. The cover 29 is removed from funnel 26 and an antifreeze solution is poured into the drum 10 through the funnel. Indicia means 30 is provided on the inside surface of the funnel 26 as a guide for determining when a predetermined level of antifreeze has been reached in the drum 10. The valves 17 and 25 are then closed and valve 14 is opened and the collector is in operation.

55 The drum 10 may be drained through drain valve 24 after vent valve 17 is opened and valve 14 is closed to discharge collected condensate. Vent valve 17 is used to 65 check the height of liquid in the drum 10 to see if draining and recharging is needed.

Drum 10 may be filled and drained very quickly without releasing the air in the system 32. The use of valves as opposed to threaded plugs or the like further ensures expeditious filling and draining. This becomes obvious, for example, when it is desired to drain only a small amount of the fluid for purposes of checking the degree of dilution. The funnel 26 serves the useful purposes of funneling the antifreeze fluid into the drum 10, of indicating the level to which the drum is to be filled with antifreeze, and of providing a sample for checking the specific gravity of the liquid.

The use of the device of the instant invention is not to be limited to dry pipe sprinkler systems but may be used in any gas pipe system where a problem of freezing condensation exists.

While the invention has been described with reference to certain embodiments, they are to be considered illustrative rather than limiting, and it is intended to cover all further embodiments that fall within the spirit and scope of the appended claims.

I claim:

1. In a dry pipe sprinkler system, an improvement consisting of a condensate collector comprising a hollow drum having a top portion and a bottom portion and a sidewall, said drum being in communication with said sprinkler system to receive condensate therefrom through an opening in said top portion, a vent valve in said top portion, a drain valve in said bottom portion, and filling means in a sidewall of said drum to enable admission of an antifreeze liquid into said drum, said means comprising a valve having a funnel thereon, said funnel being in

communication with the inside of said drum through said valve.

2. The condensate collector of claim 1 wherein said funnel has fluid level indicia means thereon.

3. In the sprinkler system of claim 1 and including a removable cover closing said funnel.

4. A device for treating and handling condensation in a dry pipe sprinkler system consisting of a hollow drum of predetermined volume having a top portion and a bottom portion and a sidewall, a shut-off valve in the top portion for connection to a low point in the sprinkler system, a fill valve in the sidewall, a funnel connected to said fill valve for enabling the filling of said drum and the period testing of the solution of antifreeze and condensate, indicia means on said funnel for indicating the amount of antifreeze in said drum, a vent valve in said top portion for venting said drum when draining and for testing the filled status of said drum, and a drain valve in the lowermost part of said bottom portion for draining said drum.
